UNITED STATES PATENT OFFICE.

FERDINAND SPLITTSTOSER, OF NORTH BRANCH, MINNESOTA.

POISON-DISTRIBUTER.

No. 817,813.

Specification of Letters Patent.

Patented April 17, 1906.

Application filed March 17, 1905. Serial No. 250,517.

To all whom it may concern:

Be it known that I, FERDINAND SPLITTSTOSER, a citizen of the United States, residing at North Branch, in the county of Chisago 5 and State of Minnesota, have invented certain new and useful Improvements in Poison-Distributers; and I do hereby declare the following to be a full, clear, and exact description of the invention, such as will enable others skilled in the art to which it appertains to make and use the same.

My invention relates to poison-distributers adapted for use to spray potato-vines and various other plants with a liquid poison, and has for its object to improve the same in the 15 several particulars hereinafter noted.

The invention consists of the novel devices and combinations of devices hereinafter described, and defined in the claims.

20 In the accompanying drawings, which illustrate the invention, like characters indicate like parts throughout the several views.

Referring to the drawings, Figure 1 is a plan view of the improved machine. Fig. 2 25 is a transverse vertical section on the line x^2 x^2 of Fig. 1, some parts being left in full. Fig. 3 is a section on the line x^3 x^3 of Fig. 2, and Fig. 4 is a section on the line x^4 x^4 of Fig. 1.

The numeral 1 indicates the wheels, the numeral 2 the axle, and the numeral 3 the frame, of a two-wheeled truck, said frame being provided with shafts 4 and a whiffletree 5. One of the wheels is fixed on the axle 2 and the other is loose, so that the said axle will be 30 positively driven under the advance movement of the machine, and at the same time the machine is adapted to turn corners, since the two wheels are independently movable.

Upon the frame 3 is mounted a barrel-like 40 tank 6, shown as disposed horizontally with its axis extending longitudinally of the machine. In its upper portion this tank is provided with a large disk-like inlet-spout 7, which is normally closed by a disk-like lid 8. 45 In the bottom of said tank in a line with said spout 7 is a cylindrical discharge-spout 9, which extends considerably above the extreme bottom of said tank. Working telescopically within the discharge spout or cylinder 50 9 is a piston-like valve 10, which is provided with a plurality of vertical passages that are adapted under a downward movement of said valve to be closed by a flexible disk-like flapper 11, secured at its central 55 portion to the hub of said valve. Under an upward movement of said valve its flapper

11 yields downward and opens up the passages in said valve. Said valve is rigidly secured to the lower end of a long vertically-disposed valve-stem 12, the upper end of which works through a central perforation in the lid 8 and is pivotally attached to one end of a walking-beam 13, which is centrally pivoted to a bracket 14, rigidly secured to the exterior of the tank 6. A conical screen 15 is secured to the lower end of the valve-stem 12 and to the marginal upper portion of the valve 10 in such manner that any liquid passing through the outlet-tube 9 must pass through said screen or filter. Rigidly secured to the valve-stem just above said screen or filter and just above the outlet-tube 9 is a disk-like deflecting-plate 16, and rigidly secured to said stem above said deflector is a perforated agitator in the form of a bracket 75 having laterally-extended perforated feet or flanges.

To the outer end of the walking-beam 13 is loosely pivoted a pitman 18, carried by the crank of a shaft 19, mounted in suitable 80 bearings 20 on the truck-frame 3. The main body portion of this crank-shaft 19 is angular in cross-section, and mounted thereon for sliding movements is a spur-pinion 21, which is subject to a shipper-lever 22, pivoted to a 85 bearing 23, rigidly secured on the adjacent side of the tank 6. Normally this pinion 21 meshes with a spur-gear 24, rigidly secured to the axle 2. By the lever 22 the pinion 21 may be slid laterally into and out of mesh 90 with the gear 24, so as to throw the crank-shaft, and hence the piston of the pump, made up of the cylinder 9 and piston-valve 10 11, into and out of action at will.

The cylinder 9 at its lower end opens into a 95 valve-chest 25, rigidly secured to the bottom of the tank 6 and provided with a discharge-port 26, in which is mounted a check-valve 27 of the flapper type, which valve permits an outward flow of the liquid, but prevents a 100 return or backward flow. A discharge-pipe 28 leads outward and forward from the discharge-port 26 and, as shown, terminates in a pronged coupling 29. Flexible discharge pipes or hose 30 are coupled onto the prongs 105 of the coupling 29, and these hose-sections lead to discharge-nozzles 31, shown as supported by levers 32, mounted on supporting-rods 33, suitably secured, as shown, to the transverse beam of the shafts or thills 4. 110 These nozzles 31 stand in position to discharge the poison liquid in the form of a

spray onto the plants, and they are preferably made movable, by means which, however, forms no part of my present invention.

At the intermediate portion of the discharge-pipe 28 is a short vertical tube 34, which opens into the bottom of a bulb-like air-chamber 35. An overflow-pipe 36 leads upward from the top of the air-chamber 35 and is provided with a depending section 36^a, the open lower end of which terminates near the bottom of said air-chamber. The upper end of the pipe 36 opens into the lower end of a valve-casing 37, and a supplemental section 38 of the overflow-pipe leads from the side of said casing and opens into the upper portion of the tank 6. The passage through the casing 37 is normally closed by a recessed valve 39, in the recess of which is placed a coil-spring 40. Working through the top of the casing 37 is an adjusting-screw 41, the lower end of which telescopes into the valve 39 and presses on the upper end of the spring 40. By adjustments of the screw 41 the tension of the spring 40 may be varied, so as to hold the valve 39 closed under any desired tension.

The numeral 42 indicates a driver's seat, shown as secured to the top of the forward end of the tank 6.

Operation: The operation of the improved machine is substantially as follows: Under the forward movement of the machine vertical reciprocating movements are imparted to the valve-stem 12 and to the parts carried thereby—to wit, to the agitator 17, reflecting-plate 16, the strainer 15, and to the piston-valve 10 11—and under such movements the liquid poison is kept thoroughly mixed, so that no sediment is allowed to accumulate in the bottom of the tank, and the said liquid is forced in a continuous stream out through the discharge-pipe 28. The main portion of the liquid will be discharged from the nozzles 31; but that portion which does not find its escape from said nozzles will be forced into the air-chamber 35, and when the pressure is sufficient to overcome the spring of the overflow-valve 40 said valve will be opened and a portion of the liquid will be returned to the tank 6. The air confined in the chamber 35 above the lower end of the pipe-section 36^a cannot escape from said chamber, and hence is compressed and its tension on the liquid in the discharge-pipe 29 keeps up an uninterrupted flow or discharge from the spray-nozzles 31 while the pump-piston is making its upward inoperative stroke. The tension under which the air confined in the chamber 35 will act to maintain a continuous

flow or discharge from the spray-nozzles may be varied by adjusting the tension of the 60 valve-spring 40.

The machine described while simple and of comparatively small cost has a large capacity and is generally efficient for the purposes had in view.

From what has been said it will be understood that the machine described is capable of modification within the scope of my invention as herein set forth and claimed.

What I claim, and desire to secure by Letters Patent of the United States, is as follows:

1. The combination with a wheeled truck and a tank mounted thereon, of a cylinder-and-piston pump extending through the bottom of said tank, an agitator rigidly and directly secured to the pump-piston, a strainer also rigidly and directly secured to said pump-piston, means for reciprocating the pump-piston under an advance movement of the machine, and an outlet-tube leading from 80 said pump, substantially as described.

2. The combination with a wheeled truck and a tank mounted thereon, of a cylinder 10 projecting through the bottom of said tank, a piston-valve working in said cylinder and 85 provided with a stem 12 working upward through said tank, a walking-beam mounted on said tank and attached at one end to the upper end of said stem 12, an agitator 17 applied to said stem, a strainer 15 secured to 90 and covering said piston-rod, a crank-shaft driven from one of the wheels of said truck, a pitman connecting said crank-shaft to said walking-beam, and a delivery-tube leading from said pump and terminating in a spray- 95 nozzle, substantially as described.

3. The combination with a wheeled truck and a tank mounted thereon, of a cylinder-and-piston pump extending through the bottom of said tank, means for operating said 100 pump under the advance movement of the machine, a valve-chest surrounding the lower portion of said cylinder, an outlet-tube leading from said valve-chest to a spray-nozzle, an air-chamber communicating with the intermediate portion of said outlet-tube, and an overflow-pipe leading from the upper portion of said air-chamber back into said tank, substantially as described.

In testimony whereof I affix my signature 110 in presence of two witnesses.

FERDINAND SPLITTSOSER.
